UNITED STATES PATENT OFFICE.

ALBERT MALSIN, OF NEW YORK, N. Y.

LADY'S SKIRT.

1,103,148.

Specification of Letters Patent.

Patented July 14, 1914.

Application filed September 15, 1913. Serial No. 789,732.

To all whom it may concern:

Be it known that I, ALBERT MALSIN, citizen of the United States of America, residing at New York, in the county of New York and State of New York, have invented certain new and useful Improvements in Ladies' Skirts, of which the following is a specification.

The present invention relates to ladies' skirts, in which the fullness or excessive width of the skirt is gathered together by means of elastic bands as described and claimed in my prior application Serial No. 624,566, filed May 2, 1911.

Owing to the gathering of the skirt or the plaits the skirt has a very clumsy appearance and it is the object of this invention to provide means whereby the plaits may be covered up without diminishing or 20 in anywise affecting the elasticity of the skirt and without rendering the skirt cumbersome.

My invention will be fully understood by reference to the accompanying drawing in 25 which—

Figure 1 illustrates in elevation one form of construction of my skirt; Fig. 2 a cross section thereof and Figs. 3 and 4 show in elevation two other forms of construction, 30 similar reference characters denoting corresponding parts.

With reference to Figs. 1 and 2, *a* denotes the skirt, which by an elastic band arranged along the waist line is gathered or 35 plaited as at *a'* to be adjustable in width, in order to fit different waist measures, but particularly to serve as a so-called maternity skirt. These plaits render the skirt objectionable. In order to improve the appearance of the skirt, I provide an appliance, whereby the plaited part of the skirt will be covered up, while the elasticity of the skirt will not be affected. This appliance consists of a band of cloth *b* having 40 a width about equal to the length of the plaits and the ends of which by elastic bands *b'* are fastened to the skirt at the seams *a'*. Sewed to the skirt at their outer ends, at *d'*, are two strap like pieces *d* of the same material as the skirt and of the same width as the band *b*. These straps or flaps are adapted to extend toward one another. The band *b* is provided near its ends with longitudinal recesses or slits *b''* through which extend the 45 threads *e'* fixed to the skirt, as at *e''*, at one end and carrying buttons or beads *e'''* at

their opposite ends. These buttons or beads rest against the outer faces of the straps or flaps *d* and hold the latter flatly against the band *b*. The object of these straps or flaps 60 is to cover up the elastic bands *b'* of the strap or band *b*. The inner or opposite ends of these straps will in normal condition of the skirt, that is when not expanded, be closer to one another, than when the skirt is expanded. The band *b* behind the straps will be more or less exposed according to the expansion of the skirt. In any case the band *b* will cover the plaits, while the straps will 65 cover the elastic bands *b'*. During the expansion of the skirt in width the threads carrying the buttons or beads will be displaced along the slits in the band *b*.

The modification, according to Fig. 3, presents a simplified construction accomplishing the same object. Here two straps *f*, *f'* are provided, which at their outer ends are stitched to the skirt at the seams *a'*. These straps are made wide enough to cover the entire length of the plaits *a''* and long 80 enough to overlap one another. At their ends the same are reduced in width. One of the straps is provided on its outside with a loop *f''* and an incision *f'''* through which the reduced portion of the opposite overlapping strap is passed behind the former. The ends of the straps carry elastic bands *g* which are secured to the skirt at the seams *a'* behind the straps *f*, *f'*. When the skirt is expanded in width the two straps will 85 yield, sliding upon one another, without exposing the plaits.

In the modification, according to Fig. 4, the construction is still more simplified. Here the straps or flaps *h*, *h'* which are 90 adapted to cover the plaits *a''* are unyieldingly secured to the skirt at the seams *b'*. In normal or unstretched condition of the skirt they are each adapted to extend about the entire width of the skirt between the 100 two seams *b'*, *b'* and to entirely overlap one another. One of the flaps or straps has a number of buttons or hooks *i* arranged longitudinally on its outer face, while the other has a number of button holes or eyelets *j* 105 arranged, so that the flaps can be affixed to one another to always lie flatly against one another in unstretched or stretched condition of the skirt.

What I claim and desire to secure by Letters Patent is:

1. In a skirt having an elastic plaited part

to be adjustable in width, non-elastic straps attached to the exterior of the skirt and adapted to cover up the plaited part and adjustable means for connecting the said straps to one another.

5. 2. In a skirt having an elastic plaited part to be adjustable in width, non-elastic straps or flaps attached to the exterior of the skirt and overlapping one another, said straps 10 being adapted to cover the plaited part of the skirt and adjustable means for connecting said straps to one another.

3. 3. In a skirt having an elastic plaited part to be adjustable in width, a band of cloth covering the said plaited part and being elastically connected to the skirt, non-elastic straps extending toward one another and adapted to partly cover said band and means fixed to the skirt and adapted to hold

said non-elastic straps flatly against the said band. 20

4. In a skirt having an elastic plaited part to be adjustable in width, a recessed band of cloth covering said plaited part and being elastically connected to the skirt, non-elastic straps extending toward one another and adapted to partly cover said band and means attached to the skirt by threads passed through the recessed portions of said band for holding the said straps flatly 25 against said band.

In testimony whereof I affix my signature in presence of two witnesses.

ALBERT MALSIN.
